(57) **CLAIM**

I claim the ornamental design for a hospital cart, as shown and described.

DESCRIPTION

FIG. 1 is a left, front, top perspective view of a hospital cart embodying my new design; and,

FIG. 2 is a left, rear top perspective view thereof.

The opposite right side view is substantially similar to the left side view of FIGS. 1 and 2, but does not include the cord or the component hanging from the hand rail.

In the drawings, the broken lines represent portions of the hospital cart that form no part of the claimed design.
